UNITED STATES PATENT OFFICE.

ERIK L. NYLUND, OF DETROIT, MICHIGAN.

RAIL-JOINT.

1,397,107.

Specification of Letters Patent. Patented Nov. 15, 1921.

Application filed March 21, 1921. Serial No. 454,205.

To all whom it may concern:

Be it known that I, ERIK L. NYLUND, a citizen of the United States, residing at Detroit, in the county of Wayne and State 5 of Michigan, have invented new and useful Improvements in Rail-Joints, of which the following is a specification.

This invention has reference to improvements in connecting means for the abutting 10 ends of railway rails.

In carrying out my invention it is my purpose to produce a simple means for connecting two rail ends which are so associated with the rails and secured thereto as to hold 15 the rails against vertical or lateral movement, to permit the said rails a limited longitudinal movement necessary for expansion and contraction.

It is also my aim to produce a rail joint 20 wherein the heads as well as the base flanges of two abutting rails are notched on the outer face of said rails, to provide for a splice bar which is arranged in the fishing spaces of the rails upon the said outer face 25 or side, said splice bar being centrally formed with a projection in the nature of a foot on its lower edge, the head portion of the splice bar being received in the notches of the heads of the rails, and the foot portion 30 of the splice bar being received in the notches of the base flanges of the rails, suitable securing elements, of the usual nature, connecting the splice bar to the rails.

A further object of the invention is to 35 provide means for effectively connecting the meeting ends of two railway rails which may be secured on wooden ties and integrally formed on metallic ties.

In the drawings:

40 Figure 1 is a top plan view illustrating two rails constructed in accordance with this invention.

Fig. 2 is a front elevation of the improvement.

45 Fig. 3 is a sectional view approximately on the line 3—3 of Fig. 2.

Fig. 4 is a sectional view approximately on the line 4—4 of Fig. 2.

Fig. 5 is a perspective view of one of the 50 rail ends.

Fig. 6 is a similar view of the joint member.

Fig. 7 is a plan view illustrating the improvement in connection with a metallic tie.

55 Fig. 8 is a side elevation thereof.

Fig. 9 is a sectional view approximately on the line 9—9 of Fig. 8.

Resting on suitable ties 1 are rails 2 of the usual construction. These rails have their confronting ends abutting, and the said rails, 60 upon the outer sides thereof have their head portions notched as at 3, the notches being of a depth equaling the distance between the side of the web 4 of the rail and the outer side of the head thereof. In a like 65 manner the base flanges 5 of the said rails, upon the said outer faces thereof are notched as at 6, and these notches terminate flush with the sides of the webs of the rails.

The connecting member for the rails includes a fish plate 8 of any determined length designed to be received in the fishing spaces of the rails and to contact with both the under face of the heads of the rails and the upper face of the base flanges of 70 the rails. The bar 8 is of a thickness greater than the depth of the notches 3 and is centrally provided with an upstanding portion which I shall term a head and which is designated by the numeral 9. The head 9 is 75 designed to be received in the notches 3 and to have its upper surface flush with the tread surface of the heads of the rails. The head 9 being of a thickness equaling that of the body of the plate 8 is projected a 80 suitable distance beyond one side of the heads of the rails.

Integrally formed on the lower edge of the bar 8 at the center thereof is a foot portion 10 that is snugly received in the notches 6 90 and which projects a suitable distance outward of the said notches beyond the edges of the base flanges 5. The upper face of the foot 10 is inclined as indicated by the numerals 11.

The bar 8, adjacent to the ends, and at equal distances from the center thereof is provided with elongated holes 13. On the inner faces or sides of the rails, and in the fishing spaces thereof is preferably arranged 100 a plate 14 that is also provided with openings alining with the openings in the plate 8 and in the webs of the rail. Through these alining openings pass bolts 15 on which are screwed the usual nuts 16. The foot 105 10 is provided with openings through which spikes are driven, as illustrated in Figs. 1 and 3 of the drawings, when the improvement is employed in connection with a wooden tie. It is one of the objects of the 110

invention, however, to employ the improvement in connection with metal ties, and in Figs. 7 to 9 of the drawings such construction is illustrated.

5 In Figs. 7 to 9 the rails 17 have their heads, upon their outer faces notched as previously described, and their base flanges likewise notched. In the pockets provided by the notches of the alining rails 17 is received the head 18 of the connecting means. The head is integrally formed on and projects centrally from a plate 19, the said plate being of any desired length and being of a width to be snugly received in the fishing 15 spaces of the rails and to contact with the upper face of the base flanges and the under faces of the heads of the said rails. The plate 19 is provided with openings which align with similar openings in the webs of 20 the rail, certain of the openings of the rails being disposed near the ends thereof and outward of the shoulders provided by the notched or cut-away head and base flanges of the said rails. Through these alining 25 openings pass bolts 20 that are engaged by nuts 21.

The plate 19, directly in a line with the head 18 is integrally formed with an outwardly extending foot portion 22 against 30 the ends of which the shoulders provided by the cut-away or notched base flanges of the rails 17 contact. The upper face of the foot is inclined as indicated by the numeral 23, and the said foot is welded or otherwise 35 secured on the upper flange 24 of a metallic I-tie 25. By this construction it will be seen that the rails may be easily and quickly connected and supported and held on the metallic ties, the bolts 20 passing through 40 openings in angle plates 26 on the inner sides of the rails as illustrated in Fig. 9 of the drawings. It will be thus seen that except for the bolts and nuts no auxiliary 45 means are employed for holding the rails connected or for holding the rails on the ties.

The improved tie joint and rail splice brace can be arranged on the tie in such a manner, especially in curves in the road, that on the inside of the curve the splice 50 is so fixed to the tie that the same will be

arranged inside of the rails, and thus the improvement may be used on both sides of the rails. The rail braces are arranged so that the rail on one side of the track is on the outside of the rail brace and the other side on the inside, so that in exchanging the rails from one side to the other those rails that were on the inside of the joint splice will now be on the outside and on the other side of the track, and those that were on the outside will be arranged on the inside of the splice. In this case, however, the inside splice brace will be slightly modified and at the top only so that the rail brace will align with the inside edge of the rail ball or head sufficiently therebelow as to not obstruct the flange on the wheels of the rolling stock. The openings in the splice may be elongated, and it is believed that the foregoing description, when taken in connection with the drawings will fully set forth the construction and advantages of the improvement to those skilled in the art to which such inventions relate. It is also to be stated that while the drawings and description refer to a satisfactory embodiment of the invention as it now appears to me, such changes may be made therefrom as fall within the scope of what is claimed.

Having thus described the invention, what is claimed as new, is:—

In combination with the abutting ends of two railway rails which have their heads and their base flanges upon their outer faces notched at the abutting ends thereof and the said notches terminating in the plane of the webs of the said rails, of a supporting tie beneath the rails at the meeting ends thereof, said tie comprising a metal member integrally formed upon its upper face with a foot, a laterally extending plate on said foot, a head on said plate opposite the foot, said head and foot designed to be received in the notched portions of the heads and base flanges on the rails when the plate is received in the fishing spaces of the said rails, and transverse means connecting the rails to the plate.

In testimony whereof I affix my signature.
ERIK L. NYLUND.
